UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

WATER-HEATER.

1,275,293.

Specification of Letters Patent. Patented Aug. 13, 1918.

Application filed August 30, 1912. Serial No. 717,922.

To all whom it may concern:

Be it known that I, HENRY W. O'Dowd, a citizen of the United States, and a resident of Jersey City, Hudson county, State 5 of New Jersey, have invented certain new and useful Improvements in Water-Heaters, of which the following is a specification.

This invention relates to water heaters, and more particularly to water heaters for 10 household use.

Objects of the invention are to provide a heater of the character referred to which shall be simple and durable in construction and efficient and economical in operation: 15 and whose parts shall be simple, compactly and conveniently arranged and adapted to be readily taken apart and reassembled. These and other objects of the invention will be in part obvious and in part more fully 20 explained in the following description.

The invention consists in the novel parts, improvements, combinations, and features of construction herein shown and described.

In the accompanying drawings, which 25 are referred to herein and form a part hereof, is illustrated an embodiment of the invention, the same serving in connection with the description herein to explain the principles of the invention.

30 Of the drawings:

Figure 1 is a side elevation of an embodiment of the invention;

Fig. 2 is a vertical central section of the same; and

35 Fig. 3 is a plan view of a preferred form of burner used in said embodiment.

Referring now in detail to the drawings, the embodiment of the invention illustrated comprises a heating coil 5 joined by 40 unions 6 and 7 to the inlet pipe 9 and outlet pipe 10, respectively, of the water system, as shown said inlet and outlet pipes being on a true axis of the coil. Surrounding said heating coil is a casing 12 having a top 13 from which leads a flue 14 for the escape of 45 the heated products of combustion.

Suitable means are provided for heating the water as it passes through the coil 5, the same, preferably and as shown, comprising 50 an annular burner 16 which has a break in

its periphery, see Fig. 3, so that the burner may be readily removed upon lifting the casing 12 or opening the door thereof without hindrance from the water supply pipe. Said burner is connected to a fuel supply 55 by a depending mixing tube 18, a nipple 19 of the burner resting upon a flange 20 of the mixing tube, said flange 20 resting in turn upon a downwardly flanged plate 22 which is secured to the water inlet and which 60 is supported, as at 23, Fig. 2, by a pedestal upon which rests the casing 12. This pedestal forms no part of the present invention, and therefore its relative position is indicated by dotted lines only. Further 65 to increase the efficiency of the burner a plurality of radial extensions 25 of the burner project inwardly, and throughout the upper surface of the burner and extensions are suitably disposed upwardly directed perforations 26. The extensions or branches 25 terminate short of the coil's center, preferably. 70

Surrounding the heat zone or lower part of the casing 12, is a hollow belt 28, formed 75 by an outer plate spaced apart from the said casing and joined thereto at the edges, so as to provide a pocket for secondary air to be supplied to the burner 16. It will be obvious that the belt 28 also conserves the 80 heat in the said zone and around the end of the coil therein. Preferably in the lower part of the belt 28 are formed a plurality of air inlets 29 which communicate with similar inlets 30 formed in the inner casing 85 12 and preferably on a level with the flame from the burner 16. It will be seen that this relative disposition of the said air inlets in the outer belt and inner casing is most advantageous for supplying atmospheric air 90 to the burner 16 in order to maintain combustion. To afford a further supply of air so as to maintain combustion ports 30^a are formed in the plate 22 through which ports the air enters and passes through and around 95 the burner to the place of combustion.

In order that the heated products of combustion may be utilized to the best advantage in their passage through the casing 12 a tubular baffle or deflector 32 having a cone- 100

shaped lower end is arranged inside the upper rings of the heating coil 5 and, as shown, has a flanged top 33 resting upon a centrally apertured diaphragm 34, extending 5 across the interior of the casing 12, over the upper end of the said coil 5. The deflector 32 fills the aperture in the diaphragm 34 and extends downwardly therefrom to approximately the level of the belt 28 aforementioned, that is, down to a point nearly in line with the upper edge of the said belt. It will be perceived that this deflector turns the heat currents from the zone of the burner 16 toward the internal surface of the surrounding 10 casing and forces them across the spirals of the coil above the said zone. At the same time the diaphragm operates to repel the ascending currents downward against the entire coil, and thus assists in maintaining 15 the latter in a permanently hot atmosphere.

The diaphragm 34 aforesaid is placed at some distance from the top of the casing 12, and forms in the upper part of the latter a separate chamber, through which the outlet 20 pipe 10 reaches the coil 5, by a suitable connection, as shown. This discharge connection of the coil 5, it will be observed, is central relatively to the axis of the deflector 32, which latter transmits to the said chamber 25 the products of combustion that accumulate and press up against the underside of the diaphragm. Suitable vents in the sides of the deflector 32, and registering perforations 37 in the top 33 thereof, enable the 30 products of combustion thus to be transmitted to the chamber, inside of which they spread around the said discharge connection, imparting thereto such heat as they may still retain after traversing the diaphragm. 35 Finally, the products of combustion are allowed to escape through a flue 14, communicating with a suitable opening in the top of the casing 12, at or near its periphery.

Besides the said vents, which are designated 40 by the reference numeral 32^a, the tubular deflector 32 is also provided with a suitable opening to receive and let pass the curved portion of the outgoing end 5^a of the coil 5. The opening may be in the form of a 45 U-shaped notch or slot 32^b, in the upper end of the deflector, as indicated by dotted lines in Fig. 2. The end 5^a of the coil is embraced by the before mentioned flanged top 33 of the deflector, and with the union 7 forms the 50 discharge connection above described, which leads into the outlet pipe 10.

It will be seen that a water heater constructed in accordance with this invention carries out the objects of the invention as 55 hereinbefore set forth and also possesses other advantages which will be apparent to those skilled in the art.

The invention in its broader aspects is

not limited to the precise construction shown and described, as many changes may be made 65 in the details thereof without departing from the main principles of the invention or sacrificing its chief advantages.

I claim:

1. A water heater including in combination a vertical coil, a casing therefor, a heating element under said coil within the lower end of said casing, a diaphragm traversing the upper end of the latter so as to form a separate chamber for products of combustion flowing around the outlet of the coil, and a coöperating member projected downwardly from said diaphragm with a passage leading the products of combustion from said element into said chamber. 70

2. A water heater including in combination a casing, a coil therein, a heating element below said coil, a diaphragm above the latter forming a separate chamber between the upper end of the coil and the top of said casing, an outlet pipe leading off the casing top, a connection between said upper end of the coil and said pipe passing through said chamber, and means conveying heat from said element into said chamber centrally of 85 said diaphragm and around said connection. 90

3. A water heater including in combination a vertical coil, a casing therefor, a heating member beneath said coil in the lower part of said casing, a diaphragm above the 95 coil separating it by an intervening space from the casing top, the discharge end of the coil leading from said diaphragm to said top across said space, an apertured element secured to said diaphragm conveying heat 100 from said heating member around said discharge end, and means affording an exit to the products of combustion passing through said element. 105

4. A water heater including in combination a vertically disposed coil, a casing enclosing the same, a burner beneath said coil, a diaphragm above the latter forming a separate chamber between it and the top of said casing, the outlet end of the coil rising 110 to the upper part of said chamber and casing top past said diaphragm, a tubular heat deflector in said diaphragm having an egress opening adjacent to said outlet end, and a flue serving to convey the products of combustion from said burner out of said chamber. 115

5. A water heater including in combination a vertical coil, a casing therefor, inlet and outlet pipes for said coil axially projecting from the opposite ends of said casing, a burner positioned in the lower part of the casing so as to throw heat around the inlet pipe, a diaphragm above the coil completely separating it by an intervening space from 120 the casing top, a tubular deflector in the 125

center of said diaphragm leading the products of combustion from said burner against the outlet pipe centrally of the space between the casing top and the diaphragm, and a flue 5 having a peripheral communication with said space at a point remote from the outlet pipe.

In testimony whereof, I have signed my name to this specification, in the presence of two subscribing witnesses.

HENRY W. O'DOWD.
